Fig. 4.

Fig. 6.

Fig. 5.

A cross-sectional diagram of a lock mechanism. The diagram shows a cylindrical body with various internal parts labeled with numbers. At the top, a curved part is labeled 9. Below it, a rectangular component is labeled 10. To the left, a vertical part is labeled 14. Further down, a horizontal part is labeled 13, and a vertical part next to it is labeled 11. On the right side, a curved part is labeled 15. At the bottom, a rectangular component is labeled 18, and a vertical part next to it is labeled 17. A small circle is labeled 5. The entire assembly is shown within a rectangular frame with diagonal cross-hatching.

UNITED STATES PATENT OFFICE.

KAŽIMIERZ PRAŽMO, OF NEW YORK, N. Y.

LATCH-LOCK.

1,180,943.

Specification of Letters Patent. Patented Apr. 25, 1916.

Application filed January 18, 1916. Serial No. 72,725.

To all whom it may concern:

Be it known that I, KAŽIMIERZ PRAŽMO, a subject of Russia, and a resident of the city of New York, borough of Manhattan, in the 5 county and State of New York, have invented a new and Improved Latch-Lock, of which the following is a full, clear, and exact description.

This invention relates to latch locks and 10 relates particularly to locks of that type in which the bolt is capable of being thrown from the normal latch position to locking position, or vice versa, by a key.

The invention has for its general objects 15 to improve and simplify the construction and operation of locks of the character referred to so as to be reliable and efficient in use, comparatively simple and inexpensive to manufacture, and so designed as to 20 afford the maximum safety.

A further object of the invention is the provision of a novel form of stop catch for 25 the bolt, whereby the same can be locked against movement in either normal or un-

locked position.

A further object of the invention is the provision of a simple, novel and effective spring device for yieldingly holding the bolt in normal condition.

With such objects in view, and others 30 which will appear as the description proceeds, the invention comprises various novel features of construction and arrangement of parts which will be set forth with particularity in the following description and claims appended hereto.

In the accompanying drawing which illustrates one embodiment of the invention and wherein similar characters of reference indicate 35 corresponding parts in all the views, Figure 1 is a perspective view of the lock before the same is applied to a door; Fig. 2 is a perspective view seen from the face side; Figs. 3 and 4 are longitudinal sections showing the bolt locked in two different positions; Fig. 5 is a transverse section on the line 5—5, Fig. 3, showing the bolt locked by the stop catch; and Fig. 6 is a similar view showing the stop catch in unlocking 45 position.

Referring to the drawing, A designates the casing of the lock which has a removable plate 1 fastened to the open side, which is presented to the door; and movable out of 50 an opening 2 in one of the end walls is the beveled end 3 of a sliding latch bolt 4

which is suitably guided in the casing A. This bolt has a rectangular portion 5 and a shank 6, and at one edge are slots or shoulders 7 and 8 in the shank of the bolt 60 for engagement by the stop catch 9. This catch is in the form of a button 10 disposed outside the casing and formed with a tongue or shank 11 which extends into the casing through a slot 12, and on this shank 11 is 65 a pin 13 which engages behind a spring 14 fastened within the casing and slotted to straddle the shank 11. This shank 11 is adapted to engage either one of the shoulders 7 or 8 to lock the bolt 4 against movement from the positions shown in Figs. 3 and 4. The spring 14 is a friction device for holding the stop catch 9 in either of its extreme positions, as shown in Figs. 5 and 6, the stop catch in the former figure serving to lock the bolt, while it is released from the bolt in Fig. 6, so that the bolt can be operated either by a key or a knob 15 fastened to the bolt and extending outwardly through the front of the lock casing. The 80 button 10 on the stop catch has a surface of considerable area in frictional contact with the outer face of the casing, and consequently the stop catch will remain in either position without danger of accidentally 85 shifting.

The latch bolt 4 is urged outwardly by a spring device which consists of a follower 16 which engages behind the shoulder 17 formed by one end of the body 5, and this 90 follower is fastened to a rod 18 which slides in bearing lugs 19 on a supporting frame 20 fastened in the casing, and surrounding the rod 18 is a spring 21 which has an end 22 bearing against one of the lugs 19, and 95 an end 23 connected with the rod 18. Thus, when the latch bolt is moved inwardly the spring 20 is compressed and serves to return the latch bolt to normal position. This spring device for the latch bolt is disposed 100 at the side of the casing opposite from the stop catch 9.

Coöperating with the latch bolt 4 are tumblers in the form of plates 24 which swing on a pivot post 25, and these plates 105 are formed with suitably shaped slots 26 in which extends the baffle post 27 of the latch bolt 4. Each tumbler is backed by a spring 28 for holding the edges 29 in proper relation to the bit of a key that is inserted in 110 the lock. A key B is adapted to be inserted through a keyhole 30 and guide 31 and to

engage not only the edges 29 of the tumblers but also the spaced slots 32 and 33 in the bolt. The slot 32 is the one engaged by the key for unlatching the bolt or moving 5 the same inwardly from its normal position, and the slot 33 is adapted to be engaged by the key when retracting the bolt from its safety locking position shown by dotted lines in Fig. 1, to the latching position 10 shown by the full lines. The key makes only a little less than a full turn in unlatching the bolt, but in completely withdrawing the bolt from its safety locking position almost two turns of the key are necessary. 15 The combination of the tumblers can be readily changed whenever desired.

From the foregoing description taken in connection with the accompanying drawing, the advantages of the construction and 20 method of operation will be readily understood by those skilled in the art to which the invention appertains, and while I have described the principle of operation, together with the device which I now consider to be 25 the best embodiment thereof, I desire to have it understood that the device shown is merely illustrative and that such changes may be made when desired as fall within the scope of the appended claims.

30 Having thus described my invention, I claim as new and desire to secure by Letters Patent:

1. A lock of the class described comprising a casing, a bolt mounted therein and 35 having spaced shoulders, said casing having a slot in its wall, a stop catch having a shank extending into the casing through the slot to engage the shoulders of the bolt, and a head bearing against the outer surface of the casing, a pin extending through 40 the shank, and a leaf spring fastened in the casing and having a free portion extending between the pin on the shank and the wall through which the shank extends, whereby 45 the pin is frictionally engaged with the spring and the head of the stop catch is frictionally engaged with the outer surface of the casing, said spring being slotted to receive the shank.

50 2. A lock of the class described comprising

ing a casing having a slot, a bolt slideable in the casing and having spaced shoulders, a stop catch in the form of a button disposed outside the casing and a shank extending through the slot into the casing for engaging either of the shoulders, a leaf spring fastened in the casing adjacent the slot thereof, and means on the shank for frictionally engaging the spring and maintaining the button of the catch in frictional engagement 60 with the outer surface of the wall of the casing.

3. A lock of the class described comprising a casing having a slot, a bolt movable in the casing and provided with spaced 65 shoulders at the side of the bolt adjacent to the slot in the casing, a stop catch in the form of a button disposed outside the casing, and a shank extending through the slot into the casing to engage either of the shoulders of the bolt, a slotted leaf spring fastened in the casing and having its slot in alignment with the slot of the casing to receive the shank of the catch, and a pin in the said shank frictionally engaging the 75 spring, whereby the latter holds the catch in position engaged with or disengaged from the bolt.

4. A lock of the class described comprising a casing, a bolt therein, and a spring 80 device for automatically returning the bolt to normal position, said device being located to one side of the bolt and consisting of a follower engaging the bolt when the latter is in normal position, a rod connected 85 rigidly with the follower, a frame fastened in the casing to one side of the bolt and having bearings for the rod, and a spring connected with the rod and adapted to compress when the bolt is withdrawn, whereby 90 the tension of the spring serves to return the bolt to normal position.

In testimony whereof I have signed my name to this specification in the presence of two subscribing witnesses.
